COMBINED DRINKING GLASS AND BRUSH HOLDER AND SHELF

Hans J. Kunz, 257 Village Lane,
Grand Junction, Colo. 81501

Filed Aug. 5, 1966, Ser. No. 3,361

Term of patent 14 years

(Cl. D4—3)

FIG. 1 is a perspective view of a combined drinking glass and brush holder and shelf, showing my new design.

FIG. 2 is an elevational view taken from the right end thereof.

FIG. 3 is an elevational front view thereof.

FIG. 4 is a top plan view, and

FIG. 5 is an elevational view taken from the left end thereof.

The fragmentary broken line representation of a wall in FIGS. 1 and 2 is for purposes of illustration only.

I claim:

The ornamental design for a combined drinking glass and brush holder and shelf, substantially as shown and described.
